UNITED STATES PATENT OFFICE.

SYLVESTER EVANS, OF WOODHAVEN, NEW YORK, ASSIGNOR TO JOSEPH BURGER, OF BROOKLYN, NEW YORK.

SHOE AND PROCESS OF MAKING THE SAME.

Application filed March 8, 1923. Serial No. 623,596.

To all whom it may concern:

Be it known that I, SYLVESTER EVANS, a citizen of the United States, and a resident of Woodhaven, Queens County, and State of New York, have invented certain new and useful Improvements in Shoes and Processes of Making the Same, of which the following is a specification.

This invention relates particularly to wooden heels and to the manner of securing the same in place.

The objects of the invention are to enable the adjustment of the heel to suit the particular condition of the shoe and to provide for drawing the heel up firmly into engagement with the body of the shoe after such preliminary adjustment.

A further object is to strengthen and rigidly brace the shoe at the point where the heel is secured.

These objects and others are attained in my invention by the employment of an anchorage plate which is first secured in adjusted relation over the heel portion of the shoe sole and which is perforated to provide gages for forcing holes up through the sole and a heel which is recessed to fit over the heel plate so that after being shifted in various directions to fit the shoe body fastenings such as screws can be driven down through the holes in the sole and plate to draw the heel into firm engagement with the sole and with its edges in close fitting engagement with the counter-portion of the shoe.

Various other novel features of the invention will appear as the specification proceeds.

The accompanying drawings are illustrative of a simple practical embodiment of the invention, wherein; Figure 1 is a broken plan view illustrating the heel plate as secured in adjusted relation over the bottom of the shoe sole.

Figure 2 is a broken sectional view illustrating one way in which said heel plate may be secured by brads or nails clinched at the inside of the sole and showing holes for the securing screws punched in the sole up through the screw holes in the plate.

Figure 3 is another longitudinal sectional view illustrating a heel adjusted in the desired relation over the plate and an awl forced down through one of the alined open-

ings in the sole and heel plate to form a seat 55 for a securing screw in the body of the heel.

Figure 4 is a similar view of the completed work, showing the screws driven down through the alined holes in the sole and plate into the heel and serving to hold the heel 60 firmly engaged with the plate and with its rim snugly fitted to the counter of the shoe.

Figure 5 is a broken cross sectional detail.

The shoe illustrated may be considered either as a new shoe to which the heel has 65 not yet been applied or as a worn shoe from which the old heel has been detached preparatory to the attachment of a new heel.

In Figure 1 the heel plate which is designated 5 is shown as secured in position on 70 the sole 6 of the shoe by brads or tacks 7 which may be clinched at the inside of the shoe, as indicated at 8 in Figure 2.

This heel plate is made of relatively light 75 and thin material which is fairly stiff and rigid, such as sheet steel and while generally flat, may be curved upwardly at its edges to more closely fit the bottom of the sole. Perforations are provided in the plate for the fastenings by which it is secured in 80 position. In the illustration there is a row 9 of such fastening perforations about the peripheral or edge portion of the plate and other perforations 10 disposed at different points longitudinally and transversely of the 85 plate within this outer row so as to provide as great a variety of fastening points as may be required. This is particularly important for repair jobs where the sole of the shoe 90 may be found to be too weak at some points to receive the fastenings and may be sufficiently strong at other points to take enough fastenings to more than compensate for any such weaknesses. The choice of fastening 95 points thus provided is also advantageous when it is considered that the plate is usually adjusted over the sole in various directions until a position is determined where the plate best fits the shoe and will provide the best reinforcement therefor.

After the plate has been fitted and secured in its adjusted relation on the sole, openings 11 for heel securing screws or fastenings are provided in the sole by forcing an awl or other cutting tool up through screw holes 12 formed in the plate. These screw holes, as indicated in Figure 1, are preferably so spaced and positioned about 100 105

the plate as to give a wide latitude of choice for the placing of the screws, the usual plan being to place some of these holes near the opposite ends and near the opposite edges 5 of the plate so that in the adjustment of the plate on the sole, one or a number of the screw holes will always be located in a good position for proper fastening of the heel. This choice of screw holes is also important 10 where the shoe has a steel shank since it enables the positioning of the screws so as to avoid the shank.

In forming the screw receiving openings in the sole the attached heel plate serves as 15 a gage by which holes are provided inside the shoe in register with the holes in the anchorage plate and through which therefore screws or other suitable fastenings can be driven to secure the heel in place.

20 The heel plate is enough smaller than the heel and the concavity in the top of the heel is deep enough to fully receive the heel plate in all the adjusted positions of both the heel plate and the heel. This enables the heel 25 being shifted in various directions over the plate and over the sole until it is brought into position where it will best fit that particular shoe and where its rim or edge will snugly engage the counter-portion of the 30 shoe.

After such adjustment of the heel to best fit the shoe in hand the openings for the screws or other fastenings are either marked or formed in the body of the heel as by 35 means of an awl or other suitable instrument entered through the guide holes previously formed in the sole. Figure 3 illustrates how this may be done by operating with an awl 13 at the inside of the shoe, by 40 inserting the point of the same through the alined openings 11, 12 in the sole and plate and forcing a screw receiving opening in the body of the heel 14. This method of operation provides screw seats in the heel 45 properly positioned to receive screws driven down from the inside of the shoe through the heel plate, regardless of the position to which the heel has been adjusted over the plate.

50 Figure 4 shows how after the screw sets have been formed in the adjusted or positioned heel, one or more screws 15, 16 may be driven from the inside of the shoe down through the alined holes in the sole and heel plate into the body of the heel and how such screws can be tightened up to draw the heel firmly up to a seat against the bottom 55 of the sole and with its edges neatly and firmly engaged with the counter-portion of the shoe. Ordinarily the heads of such screws will bottom against the upper face of the heel plate which will then provide a solid abutment for the screw to exert its pull against. After the securing screw or screws 60 are in place the fastenings which are ex-

posed at the inner face of the sole may be covered over by a suitable flap or lining piece 17.

It will be observed that all of the operations necessary for the attachment of the heel, including the nailing on of the heel plate, the formation of the screw openings in the sole, the provision of the screw seats in the heel and the driving of the securing screws down from the inside of the shoe, are such as can readily be performed by any ordinary shoe-maker and by the use of tools with which he is familiar, and further, that the adjustability of the heel plate on the sole and the independent adjustability of the heel over the plate provides a range sufficient to meet the requirements of practically any repair work that may be submitted. Also this invention enables the necessary repairs to be made even though the sole be very much weakened, as by decay of the leather, because in such instances the fastenings may be driven all about the edge of the plate so as to engage with the inturned portion of the counter and the plate be thus in effect directly fastened to the counter. The counter is usually strong enough for this purpose and the attachment of the heel plate in this fashion makes it even stronger and unifies the structure to such an extent as to enable the heel being firmly and permanently secured in proper position.

What I claim is:

1. A shoe having a sole, a substantially flat and thin heel plate having a number of nailing perforations distributed over its face and fastened in a selected position over the outside of the heel portion of the shoe sole by fastenings driven through the nailing perforations suited to the positioning of the plate on the sole, said heel plate further having an opening or openings for one or more screws providing gages for driving screw holes up through the shoe sole, a wooden heel having a cavity in its upper face freely receiving the heel plate and enabling adjustment of the heel over the sole in all directions to fit the heel to the body of the shoe and a screw or screws passed down through the screw opening or openings in the sole and in the heel plate into the body of the heel and accessible within the shoe for drawing the heel firmly up against the heel plate and sole with its edges in close fitting engagement with the body of the shoe.

2. In the application of a wooden heel to the body of a shoe, the process which comprises fitting a perforated heel plate over the outer heel portion of the shoe sole in the position where it will best brace the sole and be most firmly attached thereto and securing the same thus positioned by fastenings driven through selected perfora-

12 tions in the plate, forcing a hole or holes in the sole up through a screw securing opening or openings in the plate, then applying the concaved upper face of a wooden heel over the heel plate and shifting the heel in different directions as may be necessary to bring the same best in close fitting relation to the shoe body, boring a screw receiving hole or holes down through the hole or holes in the sole and heel plate into the body of the positioned heel and finally driving a

screw or screws down through the sole and heel plate into the body of the heel and tightening said screw or screws sufficiently from the inside of the shoe to draw the heel 15 up into firm engagement with the heel plate and sole with its edges in close fitting engagement with the body of the shoe.

In witness whereof, I have hereunto set my hand this 21 day of Feb., 1923.

SYLVESTER EVANS.
